UNITED STATES PATENT OFFICE

ISIDOR TORNBERG AND HANS C. JORDHOY, OF PLAINFIELD, NEW JERSEY, ASSIGNEES
TO WOOD NEWSPAPER MACHINERY CORPORATION, OF NEW YORK, N. Y., A CORPORATION OF VIRGINIA

HALF SPEED DECK AND INSETTING DEVICE

Application filed April 29, 1927, Serial No. 187,663. Renewed May 27, 1930.

This invention relates to that class of printing in which the web is printed and run out of the printing machine at half speed and then associated with one or more full speed webs and run into the folder to provide for producing papers, particularly newspapers, of a different number of pages from that usually necessitated by the ordinary printing presses. More specifically it is an improvement over the application for patent filed by Henry A. Wise Wood on December 3, 1926, Serial No. 152,402, in which a half speed deck is shown placed directly behind a full speed press or deck and in line with it.

The principal objects of this invention are to provide an arrangement of the half speed deck and supply rolls in such a way as to enable the half speed web to be fed in at any desired point between any of the full speed webs of a multiple newspaper printing press; to so arrange the parts that the reel for the half speed paper rolls will not take up any additional space, and to provide improvements in the way of leading the half speed web into association with the full speed webs and into the folder.

Other objects and advantages of the invention will appear hereinafter.

Reference is to be had to the accompanying drawings, in which

Fig. 1 is a fragmentary and diagrammatical side view of a double deck newspaper printing press showing one of the half speed decks or units in its relationship to the adjacent full speed decks;

Fig. 2 is a front elevation of two opposite pairs of full speed decks and a pair of half speed decks located in accordance with this invention;

Fig. 3 is a plan showing the relationship of a half speed deck to two full speed decks;

Fig. 4 is an enlarged diagrammatic side view of the means for leading the half speed web in between the two full speed webs; and

Fig. 5 is an elevation of means for supporting the reels and web rolls for one full speed deck and one half speed deck.

Referring first to Fig. 1, a pair of decks of a large printing press is shown, involving a series of full speed lower decks 10 and

full speed upper decks 11. The lower decks take their supply of paper from a corresponding number of reels 12 below, and the upper decks take their supply from a corresponding series of reels 13 above. The details of the parts that have just been referred to will not be described further, only enough of them being illustrated to show their positions with respect to each other and their relationship to the present invention.

A single folder 14 is also shown which, as will be noticed by the direction of the webs, is capable of taking the full speed webs from one or more of the upper and lower decks. This folder is arranged between two of the lower decks in the form shown, but it can be arranged in some other convenient place and is not a part of this invention.

It will be noticed that near two of the upper decks 11 we have shown a half speed printing deck 15. This is shown as located on the same level as the several upper decks. It receives its web *w* from a reel 16 which is located on the same axis as one of the reels 13, but at the side thereof.

Referring to Fig. 5 it will be seen that the two reels 13 and 16, shown in that figure, are operated by separate gears 17 and 18 on their respective shafts, which are centered on suitable supports axially in alignment with each other. Reels having three rolls are illustrated for the purpose of convenience, and each reel is operated independently of the others.

The details of the half speed printing unit 15 do not constitute a part of this invention, but it will be seen that it is located out of axial alignment with either one of the adjacent decks 11 by reference to Figs. 1 and 3.

By reference to Figs. 2 and 3, it will be seen that each one of the two decks 15 is located out of lateral alignment with the adjacent upper decks 11 and lower decks 10. In Fig. 2 we have shown the motors 18 operating vertical shafts 19 which, by means of mitre gears, operate the decks 10 and 11 located adjacent thereto. The two half decks 15, which are located just beyond the space between the two adjacent decks 11, are operated independently by their own shafts from

the main shaft of the press. Although the connections are not shown, it is intended, of course, that they shall be provided with clutches or other means for connecting them with, and disconnecting them from, said main shaft.

It will be seen in the first place that these half speed decks are out of alignment in both directions with the ordinary full speed decks. 10 They are readily accessible and are not in the way of access to the usual decks with which presses of this kind are provided. They are mounted on the frame 20 of the machine, and although they project out at the side, they 15 do not take up any floor space.

An important feature of the invention consists in the location of the reels 16 in axial alignment with some of the reels 13, as stated above. This results in an economy in space 20 at the top or at the bottom, if it is desired to place them there. They do not project out any farther into the room than the reels 13 with their rolls and occupy a space between two reels 13 which otherwise is vacant. We 25 have shown two of these decks 15, but, of course, are not limited to that number as a single deck located between the two full speed decks would be a practical construction.

The web *w* is fed through the deck 15 and 30 perfected and then turned over two turning bars 21. This brings the web *w* into alignment with the webs *W* coming from certain of the press units or decks 10 and 11. In this case three of these webs *W* are shown as co- 35 operating with the small web *w*, and the latter web is fed between a couple of cutting cylinders 22 and then led in over various guide rolls between two of the webs *W*.

The web *w* is associated with the webs *W* 40 in the manner shown in Fig. 3, and if desired, the mechanism illustrated in the said application of Henry A. Wise Wood can be used in connection therewith. The associated webs whether two, three, four, or any other number, are then brought over the drag roll 23 45 and then into the former of the folder 14.

It will be seen that by locating the half speed deck and its supply reel out of line with the main portion of the press, and in 50 fact with the adjacent full speed decks, the half speed web can be fed in, not only at the point shown in Fig. 1, but between any of the full speed webs adjacent or near thereto. This also permits of an economical arrangement 55 of the paper reels obtained from the placing of each half speed reel 16 in line with one of the full speed reels, so that it takes up no space that is otherwise occupied for any useful purpose, and does not add to the length 60 or width of the machine itself.

Although we have illustrated and described only a single form of the invention and shown only a single relative location of the parts, we are aware of the fact that 65 modifications can be made in the loca-

tion and arrangement, and especially in the types of the half speed decks and reels, without departing from the scope of the invention as expressed in the claims. Therefore we do not wish to be limited in these respects, but what we do claim is:—

1. In a printing press, the combination with a full speed web printing deck or unit, of a half speed web printing deck located adjacent to the full speed deck and parallel thereto but out of line with it laterally and longitudinally. 75

2. In a printing press, the combination with a full speed printing deck or unit and a reel for supplying the web of paper thereto, of a half speed deck located adjacent to the full speed deck but out of line with it laterally, and a reel for supplying the half speed deck located in axial alignment with the first named reel. 80

3. In a printing press, the combination with a full speed printing deck or unit and a reel for supplying the web of paper thereto, of a half speed deck located adjacent to the full speed deck but out of line with it longitudinally, and a reel for the half speed deck located in axial alignment with the reel for supplying the full speed deck. 85

4. In a printing press, the combination with lower deck and upper deck, both full speed decks, one over the other and reels for supplying said decks with webs located substantially vertically in line with the decks, of a half speed press located out of line with the regular run of the press, means for supplying the half speed deck with a web, and means for guiding the half speed web between the webs from the upper and lower decks to a folder. 95

5. In a printing press, the combination with lower deck and upper deck, one over the other, of a half speed press located out of line with the regular run of the press, turning bars for shifting the position of the half-speed web over into alignment with the full speed webs from the upper and lower decks, and means for guiding the half speed web between the webs from the upper and lower decks to the drag roll of a folder. 105

6. In a printing press, the combination with lower deck and upper deck both full speed decks, one over the other, of a half speed press located out of line with the regular run of the press, turning bars for shifting the position of the half-speed web over into alignment with the full speed webs from the upper and lower decks and between them, means for cutting the half speed web after it is turned, and means for guiding the half speed web between the webs from the upper and lower decks to the drag roll. 115

7. In a printing press, the combination with pairs of decks comprising lower decks with their printing cylinders opposite each 120

other in the press and substantially in alignment, and upper decks arranged adjacent each other and above the lower decks, and reels for supplying the upper and lower decks, of a pair of half speed decks located at one deck level and having their outer ends at a distance apart less than the distance between the two decks.

8. In a printing press, the combination with two pairs of decks comprising two lower decks with their printing cylinders opposite each other in the press and substantially in alignment, and two upper decks arranged adjacent each other and above the lower decks, and reels at the top and bottom 15 of the press for supplying respectively the upper and lower decks and in alignment therewith, of a pair of half speed decks located at one deck level and having their outer 20 ends at a distance apart less than the distance between the two decks, and reels for supplying the half speed decks with a web of paper located in alignment with the two 25 reels for supplying one of the full speed decks.

9. In a web supplying means for a printing press, the combination with a reel for supporting rolls for supplying the web to a printing press deck, and means for operating 30 it, of a second reel having means for supporting a series of rolls for a half speed deck, said second reel being located axially in alignment with the first named reel, and independent means for operating the second 35 reel.

In testimony whereof we have hereunto affixed our signatures.

ISIDOR TORNBERG.
HANS C. JORDHOY.
